UNITED STATES PATENT OFFICE

ADOLPH F. DECKER, OF EVANSVILLE, INDIANA, ASSIGNOR TO WYCKOFF, SEAMANS & BENEDICT, OF ILION, NEW YORK, A CORPORATION OF NEW YORK.

TYPE-WRITING MACHINE.

No. 897,272.

Specification of Letters Patent.

Patented Sept. 1, 1908.

Application filed June 6, 1907. Serial No. 377,600.

To all whom it may concern:

Be it known that I, ADOLPH F. DECKER, citizen of the United States, and resident of Evansville, in the county of Vanderburg and State of Indiana, have invented certain new and useful Improvements in Type-Writing Machines, of which the following is a specification.

My invention relates to typewriting machines and more particularly to a provision of simple and efficient means whereby the machine may be readily employed for making vertical lines on a sheet with the aid of the usual printing characters of the machine, such for instance, as a colon, and for leaving both hands of the operator free for performing such work.

To the above and other ends which will hereinafter appear my invention consists in the features of construction, arrangements of parts and combinations of devices to be hereinafter set forth in the specification and particularly pointed out in the appended claims.

In the accompanying drawings wherein like reference characters indicate corresponding parts in the different views, Figure 1 is a vertical central front to rear sectional view of a typewriting machine embodying my invention. Fig. 2 is a fragmentary detail side view with parts in section showing some of the parts illustrated in Fig. 1 and with the space key of the machine shown locked in the depressed position. Fig. 3 is an enlarged detail fragmentary perspective view showing the locking latch and some of the associated parts.

My invention in the present instance is shown as a simple attachment applied to a No. 6 Remington machine without the necessity of modifying any of the structural features of said machine but said attachment may be applied with equal facility and effect to other styles of typewriting machines.

I have disclosed in the accompanying drawings sufficient of a No. 6 Remington machine to illustrate the use of my attachment and to afford an understanding of the effect thereof on the machine.

The frame of the machine comprises a base 1 having a front cross bar 1^a which forms a part thereof, corner posts 2 and a top plate 3. Printing key levers 4 are provided with keys 5 and are fulcrumed on a fulcrum bar 6 in the base of the machine. Each key lever

is provided with a restoring spring 7. Links 8 are connected to the key levers and to the type bars 9 which are pivoted at 10 to type bar hangers 11 secured in the usual manner to the top plate of the machine. The usual space key levers 12 at the sides of the machine are pivoted on the fulcrum bar 6 and are connected at their forward ends by a transversely extending space bar or key 13 through angularly depressed connecting brackets 14 or otherwise.

Extending beneath the system of key levers 4 and the space keys 12 is a universal bar 15 connected at its ends to upwardly extending links 16 provided with hook-like members 17 at their upper ends for coöperation with the usual transverse bar 18 connected at 19 to a forwardly extending arm 20 of a dog rocker, the rock shaft of which is pivoted at 21 to a depending bracket 22 secured to the top plate of the machine. An upwardly extending arm 23 of the dog rocker carries a fixed feed dog 24 fixedly secured to the arm 23 and a loose dog 25 pivoted to the arm 23 at 26 so as to vibrate in the general direction of the travel of the carriage. A spring 27 coöperates with the loose feed dog to turn it around its pivot 26. A restoring spring 27^a is connected at one end to the bracket 22 and at the other end to the dog rocker so as to move the dog rocker and the parts connected therewith to normal position. The feed dogs 24 and 25 coöperate with a feed rack (circular or otherwise) which in the present instance is in the form of an escapement wheel 28. The escapement wheel is operatively connected through the usual pawl and ratchet mechanism (not shown) to a shaft 29 which rotates in a bearing 30 secured to the top plate of the machine and is provided at its forward end with a feed pinion 31. A feed rack 32 is connected to arms 33 pivoted at 34 to a carriage truck 35. The carriage truck carries rollers 36 which coöperate with a guide rod or rail 37 and is likewise provided with a rearwardly projecting arm 38 which coöperates with a second fixed guide rod 39. Links 40 are pivoted at 41 to the carriage truck and at 42 to a platen frame 43. The forward portion of the platen frame carries a grooved roller 44 which coöperates with a shift rail 45 carried by pivoted arms 46 and by means of which the platen frame may be shifted to change the case position of the cylindrical rotative

platens 47 carried thereby. The platen is connected at one end with a line spacing wheel 48 with which a spring detent roller 49 coöperates. A finger wheel 50 is secured to a platen shaft 51 at each end thereof. Line spacing devices (not shown) of the usual construction coöperate with the line spacing wheel 48 to effect a movement thereof. The parts thus far described constitute portions 10 of the well-known No. 6 Remington machine and the operation thereof is well understood.

The locking device of my present invention is best shown in Fig. 3 from which it will be seen that a bracket plate 52 is secured by 15 screws 53 to the rear side of the front cross bar 1^a of the base of the machine and at the left hand side thereof. Ears 54 are struck up from this bracket plate and are perforated to receive a pivot 55 to pivotally connect a 20 locking latch 56 to the ears. The locking latch is thus pivoted to swing in a horizontal plane and into and out of the path of the horizontal portion 14^a of the left-hand bracket 14 which connects the space key or 25 bar 13 to its left-hand lever 12. The locking latch 56 normally extends substantially parallel with the space bar or key and is provided with an upwardly extending bent portion 57 which constitutes a finger piece or 30 handle to facilitate the movement of said locking device around its pivot. The parts are so constructed and arranged that when the space key is depressed as shown in Fig. 2 and the locking latch is swung on its pivot 53 35 over the member 14^a as shown in Figs. 1 and 2, the space key will be locked in the depressed position and said space key and the parts controlled thereby cannot return to normal position until the latch is released 40 or swung back to the position shown in Fig. 1 where it is out of the path of the space key and its carrying members 14. By depressing the space key and locking it in the position shown in Fig. 2 the loose dog 25 will be 45 moved out of engagement with the escapement wheel and the fixed dog 24 will be moved into engagement therewith without the carriage having been advanced to effect a letter space movement thereof, it being 50 understood that the escapement mechanism of the No. 6 Remington machine and in fact most escapement mechanisms are what are known as "ordinary" escapements and do not effect a release of the carriage until the 55 return stroke of the key. The fixed dog being in engagement with the escapement wheel locks the escapement wheel and the carriage against movement in either direction. The depression of the space key likewise 60 carries the universal bar 15 down below the paths of movement of the printing key levers 4 so that an actuation of any of the key levers 4 at this time will actuate the associated type bar without affecting the 65 escapement mechanism and without pro-

ducing a letter space movement of the carriage. The carriage being locked both hands of the operator are free to manipulate the machine. Thus, the operator may employ one hand to actuate the key of the colon 70 mark, for example, and the other hand may be employed to turn the platen through the finger wheel 51 or through the usual line spacing mechanism. The printing operation and turning of the platen a tooth space 75 distance at a time is effected alternately and there being no feed of the carriage at this time; the imprint of the colons will occur one beneath another and a vertical dotted line will be produced on the paper. 80 When the operator has finished writing the vertical line the latch 56 may be shifted to the inoperative position shown in Fig. 1, which will result in the space key being 85 released, and the space key, universal bar and dog rocker will be restored to normal positions and the writing may be proceeded with.

While I prefer to employ a locking latch of the general character described to co-operate with the space key or the carrier therefor to secure the results specified, from a broad aspect of my invention any means for locking the escapement mechanism or carriage feed mechanism out of operation to 95 prevent a feed movement of the carriage and without affecting the operation of the printing instrumentalities may be employed.

It will be seen that my invention is useful wherever it is desired to print characters 100 without effecting a feed of the carriage as when vertical dotted lines or the like are to be written on the paper as in the preparation of legal documents for making "box" headings or the like.

105 Various changes may be made without departing from the spirit and scope of my invention.

What I claim as new and desire to secure by Letters Patent, is:—

110 In a typewriting machine, the combination of a feed rack, a holding dog, space key levers at the sides of the machine, a space bar extending transversely of the machine and connected to said levers by depressed brackets; a latch pivoted to the front bar of the base frame and normally occupying a position substantially parallel with said space bar but adapted to be swung to engage the depressed bracket when the space bar is 115 pushed down and thus lock the holding dog and feed rack in engagement.

120 Signed at Evansville, in the county of Vanderburg and State of Indiana this 29th day of May A. D. 1907.

ADOLPH F. DECKER.
